UNITED STATES PATENT OFFICE.

WILHELM KLINGNER, OF NEW YORK, N. Y.

DESIGN FOR A WARDROBE.

SPECIFICATION forming part of Design No. 12,697, dated January 17, 1882.

Application filed December 6, 1881. Term of patent 14 years.

To all whom it may concern:

Be it known that I, WILHELM KLINGNER, of the city of New York, county and State of New York, have invented a new and original 5 Design for a Wardrobe, of which the following specification is a full, clear, and exact description, reference being had to the accompanying drawing, forming part of this specification.

The drawing represents a perspective view 10 of my newly-designed wardrobe.

This invention relates to a novel configuration of the front of a wardrobe.

It consists in a wardrobe-front, A, having 15 between uprights *a a*, alternately, rectangles *b* and ledges *c*, as shown. The front is moreover provided with a forwardly-projecting central section, *d*, extending from top to bottom, and ornamented likewise with rectangles *b* and

ledges *c* to correspond to the rectangles and ledges on the remaining portion of the wardrobe front A. 20

I claim as my invention—

1. The design for a wardrobe-front, A, consisting of alternate rectangles *b* and ledges *c* between uprights *a*, substantially as shown. 25

2. The design for a wardrobe-front, A, consisting of a forwardly-projecting central section, *d*, having rectangles *b* and ledges *c* to correspond with rectangles and ledges on the remainder of the wardrobe-front, substantially as 30 shown.

WILHELM KLINGNER.
